Specification for Design.

Patented Apr. 17, 1917.

Application filed January 20, 1917. Serial No. 143,534. Term of patent 7 years.

To all whom it may concern:

Be it known that we, ROBERT Y. BARROWS, a citizen of the United States of America, residing in the town of Rutherford, in the county of Bergen and State of New Jersey, and GEORGE V. STRAHAN, a citizen of the United States of America, residing in the city of Newark, in the county of Essex and State of New Jersey, have invented a new, original, and ornamental Design for an Arm-Pan for Lighting-Fixtures, of which the following description, in connection with

the accompanying drawing, is a specification.

Figures 1 and 2 of the drawings are respectively a plan view of the underside, and a side elevation, of an arm pan for lighting fixtures, showing our new design.

We claim as our invention:

The ornamental design for an arm pan for a lighting fixture, as shown.

ROBERT Y. BARROWS.
GEORGE V. STRAHAN.
